FRACTURE TABLE

Alonzo J. Neufeld, Los Angeles, Calif., assignor to
 Alumni Research Foundation of The College of
 Medical Evangelists, Loma Linda, Calif., a cor-
 poration of California

Application January 11, 1951, Serial No. 205,494

2 Claims. (Cl. 128—84)

1

This invention relates to an orthopedic or surgical table for facilitating the examination of a patient, the setting of fractures, application of bandages, casts and the like.

It is an object of this invention to provide improved apparatus of this character.

Another object of this invention is the provision of such apparatus leaving the body largely exposed whereby the application and removal of bandages, casts and the like is greatly simplified.

Another object is the provision of such apparatus having a pelvic support and a back support, alternatively usable as conditions require.

Another object is the provision of such apparatus wherein the perineal support serves as a common means for mounting the arm and leg supporting members.

Another object is the provision of such apparatus incorporating the supporting framework, the frame and the apparatus being of knock-down construction enabling their accommodation in a small space when not in use or for ready portability.

Another object is the provision of such a frame having foldable legs arranged in a novel manner.

This invention possesses many other advantages and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

In the accompanying drawings:

Fig. 1 is a side elevation of apparatus incorporating the invention;

Fig. 2 is a top plan view thereof;

Fig. 3 is a fragmentary elevation partly in section, showing a portion of the left-hand end of the supporting frame of the apparatus of Fig. 1;

Fig. 4 is a fragmentary elevation partly in section, showing a portion of the right-hand end of the supporting frame of the apparatus of Fig. 1;

Fig. 5 is an elevation partly in section showing an alternate operating position of certain parts of Fig. 4;

Figs. 6 and 7 are cross sections taken substantially as indicated by the correspondingly numbered lines on Fig. 3 and on a further enlarged scale;

Fig. 8 is a cross section, taken substantially as

2

indicated by line 8—8 of Fig. 4 and on a further enlarged scale;

Fig. 9 is a cross section, taken substantially as indicated by line 9—9 of Fig. 5;

Fig. 10 is a detail section taken substantially as indicated by line 10—10 of Fig. 1, showing an alternate operating position of the parts;

Fig. 11 is an exploded view showing the alternatively usable pelvic and back supports of the apparatus;

Fig. 12 is a side elevation, similar to Fig. 1 but on a reduced scale and showing the apparatus in use; and

Fig. 13 is a fragmentary part sectional and part elevational view of a modified arrangement of parts of the apparatus compared to the arrangement shown in Fig. 12.

Referring to the drawings, particularly Figs. 1, 2, and 12, the apparatus is shown as comprising a supporting frame F having a generally horizontal member 10 with three supporting legs 11, 12 and 13, pivotally mounted thereon so as to be foldable, as indicated in Fig. 1. The perineal post 15 extends upwardly from one end of the member 10 and carries the cantilever leg supporting members 16 and 17 as well as the similarly arranged arm supports 18 and 19. Adjacent the opposite end of the frame member 10 a shoulder and head supporting structure generally indicated by the numeral 20 is shown, a back support 21 extending therefrom to the perineal post 15. As clearly shown in Fig. 12, the patient is supported in a prone position with his feet respectively supported by the members 16 and 17, his arms supported by grasping the members 18 and 19 respectively, his head and shoulders on the structure 20, and his back on the support 21. Suitable adjustments are provided to accommodate persons of different proportions and it will be apparent that only the minimum areas of the body are covered so as to interfere as little as possible with the examination, application of casts, etc.

Referring in detail to the structure, the horizontal frame member 10 is shown as tubular and has a pair of depending lugs 25 joined by an arcuate transverse wall 26 adjacent the head end with a transverse pin 27 on which is pivotally mounted the tubular support leg 11 for which purpose it is provided with a pair of lugs 28 at its upper end which engage the pin 27. A tubular sleeve 29 is slidable exteriorly of the leg adjacent its upper end and is urged upwardly by a tension spring 30. The upper end of sleeve 29 has an enlarged portion or collar 31 urged into engage-

ment with the wall 26 by the spring 30 (see Fig. 3) for maintaining the leg 11 in extended or supporting position. When it is desired to fold the leg to retracted position as indicated by the broken lines in Fig. 1, the sleeve 29 is urged downwardly to disengage the wall 26, freeing the leg 11 for movement about the pin 27.

The opposite end of the member 10 is provided with two pairs of lugs 33 and 34 (see Figs. 4 and 8) similarly arranged to mount legs 12 and 13 respectively, each of which is provided with a slideable locking sleeve 35.

As clearly shown in Figs. 1, 2, 3, 5 and 6, the head and shoulder supporting structure 20 comprises a short tubular post 38 forming a socket, supported on the member 10 by the aid of a short tubular section or sleeve 39 slideable on the exterior of the member 10. A guide 40 within the member 10 is secured to sleeve 39 as by screws 41 extending through a guide slot 10A in the member 10, the screws 41 cooperating with the slot 10A to maintain the post 38 upright. A nut 42 is secured on the member 40 by a screw 43 and engages a threaded rod 45 extending longitudinally in the member 10 and rotatably supported therein by a head 46 at the outer end of the member 10 and a member 47 adjacent the opposite end (see Fig. 4). A hand crank 48 is secured to the outer end of the rod 45 for imparting rotation thereto, such rotation serving to adjust the position of the post 38 and attached parts longitudinally of the member 10.

As shown in Fig. 3, the shoulder support comprises a transversely extending bowed plate 50 carrying a detachable cylindrical plug 51 which telescopes within the upper end of the tubular post 38 which latter is reinforced by a tubular liner 51a. The plate 50 rests on the end wall 50a of the plug and is detachably connected with the plug by means of a screw threaded projection 50b fixed on the wall 50a and engaged in a screw threaded opening 50c in the center of the plate. Suitable lugs at 51b provided on the upper end of the post engage in openings 51c in the plate 50 to hold the plate in the desired position.

An arm 53 is mounted on the post 38 for angular and axial adjustment thereon by the aid of a collar 54 (see Fig. 3). As shown in Fig. 6, the arm 53 is of flat sided cross section and has the head rest 55 slidably mounted thereon by means of a short vertical arm 56 having an inverted U-shaped foot 56a slidably engaging the arm 53 and secured in adjusted position therealong by a clamp screw 57. Slidable within the arm 53 is a short plunger 58 having a cylindrical portion 58a adapted to engage the post 38 through an opening 54a in the collar 54. A rod 60 engaging the plunger 58 extends longitudinally of the arm 53 and through a head 61 at the free end thereof. The rod 60 threadedly engages the head 61 so that appropriate rotation of the rod 60 by the hand grip 62 serves optionally to cause the plunger extension 58a to clamp the arm in adjusted position on the post 38 or to free it for movement as desired.

The perineal post 15 comprises a tubular socket 64 fixed on the member 16 adjacent the end thereof of remote from the head or shoulder support structure 20, upon which the leg support members 16 and 17 are mounted. Each of these members comprises a tubular portion 65 having a collar 66 rotatably engaging the socket 64 and adapted to be secured in angularly adjusted position as by conventional clamp arrangement 67. An extension 68 slidably telescopes within the member

65 being secured in longitudinally adjusted position as by clamp 69. The outer end of member 68 has a conventional foot engaging means 70 mounted thereon.

5 A tubular member 71 telescopes within the socket 64 being supported as well as angularly restrained therein by a pin or projection 71a engaging one of the notches 64a in the upper end of the socket member 64, and serves to mount 10 the arm supporting members 18 and 19. For this purpose each of these members has a hub or collar 72 engaging the member 71 for axial and angular movement thereon, being secured in adjusted position by a conventional clamp 73.

15 From the foregoing, it will be seen that not only the arm supports 18 and 19 but the leg supports 16 and 17 as well are supported solely by the post structure 15, extending therefrom as cantilevers.

20 A pelvic support 75 is also mounted on the post or socket 64 (see Figs. 4, 5, 9 and 11). This pelvic support comprises a horizontally disposed plate 76 having a depending semicircular hub 77 adapted to embrace the exterior of the socket 64 25 and to be supported on the upper end thereof as by a pair of diametrically disposed pins 78 which engage suitably placed pairs of the apertures 64a in the upper end of the socket 64 as will appear from Figs. 9 and 11. It is to be understood that 30 the post 71 will be disposed so that its pin 71a will be so located as not to interfere with the pins 78. Two pairs of apertures 64a are provided when the support 75 is disposed with the pin 78 engaging one pair of these apertures or notches 64a, the plate 76 is disposed in inoperative position where it will not support the patient. This position is shown by the full lines in Fig. 2 as well as in Fig. 11. When the pins 78 are disposed in the other pair of notches 64a, the plate 76 will be 40 disposed in an operative body engaging position substantially at right angles with the inoperative position, as indicated by the broken lines in Fig. 2.

45 The back supporting member 21 comprises a resilient strip 80 adapted to extend between the head and shoulder supporting structure 20 and the perineal post 15 and is adapted for use when the pelvic support is not desired. For this purpose the strip 80 is detachably supported by the aid of a socket arrangement at each of its ends. Thus, the pelvic support 75 has an elongated upwardly opening socket 81 adapted to receive end portion 80a of the strip 80, while the other end of the strip 80 has a similar socket 82 adapted to engage an intermediate portion of the shoulder support member 50. It will be obvious that it is 50 immaterial whether either socket is formed on the resilient strip or on the cooperating support, although it is preferably carried by the strip as it serves as a convenient grip in removing the strip from an unhardened plaster cast.

55 In applying plaster casts about the body of a patient, for example with the apparatus arranged as shown in Figs. 1 and 12, the back supporting strip A is covered by the plaster and in many instances the shoulder plate 50 and plug 51 thereof are likewise embraced by the plaster. In consequence the strip 80 and the plate 50 must be removed before the plaster hardens. Thus, when completing the cast the patient is lifted and the strip 80 and plate 50 and plug 51 are likewise 60 lifted from the apparatus. The plug 51 slips freely out of the post 38 and the end of the strip 80 likewise slips out of the socket 81 during this lifting of the patient. The plug 51 is now unthreaded from the plate 50 and the latter being 65

thin and smooth is pulled sidewise by an end out of the cast. The strip 80 is grasped at the socket 82 thereon and pulled lengthwise out of the cast.

From an inspection of Figs. 1 and 12 it will be apparent that the spacing of posts 38 and 15 is such as to curve the resilient strip 80 upwardly. When the back support 21 is not desired, the strip 80 may be readily removed by moving the head and shoulder support 20 away from the perineal post 15 which will relax the tension on the strip 80, after which the pelvic support may be swung to operative position by raising it slightly to free pins 78 from one pair of notches 64a. After such adjustment the support 75 may be lowered so that the pins 78 engage the other pair of notches 64a.

When the pelvic plate 76 is in the position shown in dotted lines in Fig. 2 and in full lines in Figs. 5 and 9 for supporting the patient, should a plaster cast be applied in a manner in which the plate is covered by the plaster, it is apparent that when the patient is lifted after completing the cast, the plate and the hub 77 thereon will be lifted from the socket 64. The plate may readily be removed from the cast before the plaster sets by grasping the hub 77 and pulling the plate outwardly in the direction of its length.

As shown in Fig. 13, the leg supporting members 16 and 17 may be removed from the tubular member or socket 64 and mounted on the post 38, the collars 66 fitting alike on the socket 64 and post 38. This arrangement is desired for shoulder spicas, the leg supporting members being extended laterally in opposite directions to 35 cooperate with the arm supports 18 and 19 to facilitate the tying and holding of the arms in desired positions for applying the shoulder spicas.

I claim:

1. In a surgical table or the like: a head and shoulder supporting structure comprising a vertically disposed post, a shoulder engaging member mounted on said post, an arm supported on said post for angular and axial movement thereon; a head supporting member on said arm, and means operable from the free end of said arm for securing said arm in adjusted position on the post.

2. In a surgical table or the like: a head and shoulder supporting structure comprising a vertically disposed post, a shoulder engaging member mounted on said post, a tubular arm extending from said post, a sleeve supporting said arm and being angularly and axially movable on said post, a head support mounted on said arm and longitudinally adjustable therealong; means for holding said head support in adjusted position on said arm; and means securing said arm in adjusted position on said post, comprising a plunger movable in said arm into and out of engagement with said post; and a rod connected with said plunger and movable in said arm for actuating said plunger.

ALONZO J. NEUFELD.
